UNITED STATES PATENT OFFICE.

GEORGE W. LADD, OF PROVIDENCE, RHODE ISLAND.

DESIGN FOR A WATCH-CASE.

SPECIFICATION forming part of Design No. 16,127, dated June 16, 1885.

Application filed June 3, 1884. Term of patent 14 years.

To all whom it may concern:

Be it known that I, GEORGE W. LADD, of the city and county of Providence, and State of Rhode Island, have produced a new and original Design for Watch-Cases, of which the following is a full, clear, and exact description, reference being had to the accompanying drawings, forming a part of this specification.

10 The design consists in a central raised surface for one or both covers of the watch-case, said surface having at its point of union with the margin of the cover two swells or curvatures, whereby a highly ornamental effect is imparted to the cover or covers.

15 In the drawings, Figure 1 is a side view of the watch-case. Fig. 2 is a similar view, partly in section, the cover being in open condition.

20 In the said drawings, A designates the case, and B designates the cover, which may be either the front or back cover of the case.

This cover has at the point of union between the raised portion b and the margin two curves or swells, $b' b''$, rising successively from 25 the margin line, whereby a very handsome and pleasing effect is imparted to the eye. The central portion, b , may be ornamented by engine-turning or engraving. The curved rim b' is in this instance left plain, so as to present a polished surface, thereby imparting a 30 rich and solid appearance to the case; but the curved rim b'' may be ornamented by engraving, and the central portion left plain.

Having thus described my invention, I claim 35 as new and desire to secure by Letters Patent—

The design for a watch-case, consisting of the centrally-raised portion b and the curves or swells $b' b''$, as shown at the point of union of the raised portion and the margin.

GEORGE W. LADD.
